UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

MULTIPLE-UNIT SAFETY-SWITCHBOARD.

1,324,161.

Specification of Letters Patent.

Patented Dec. 9, 1919.

Application filed December 26, 1917. Serial No. 208,799.

To all whom it may concern:

Be it known that I, HUBERT F. KRANTZ, residing at Brooklyn, in the county of Kings and State of New York, have invented certain new and useful Improvements in Improved Multiple-Unit Safety-Switchboards, of which the following is a specification.

This invention relates to a multiple-unit panel board and is designed as an improvement over the structure shown and described in my pending application Serial No. 184,011 filed August 2, 1917.

The object of the present improvement is to provide a structure in which the several units, which are independently removable, each comprise a substantially closed container within which certain parts of the mechanism may be held and protected at all times even after the unit is detached from the board.

A further object is to provide the detachable units with covers or doors formed as parts thereof and said doors being adapted when the units are assembled with the board collectively to constitute a protecting wall at the rear of the board.

A further object is to construct the detachable switch units each as a closed container and to provide opposite side walls of each container with extensions adapted to constitute supporting means for mechanisms exteriorly of the containers, which mechanisms may coöperate with parts of the board structure when the units are assembled with the board.

A further object is to provide an improved form of support comprised in the board structure for detachably supporting the several switch units.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown merely a preferred form of embodiment of the invention:

Figure 1 is a perspective view illustrating 55 a switch board constructed in accordance with this invention and showing one of the switch units detached and in position to be connected with the board.

Fig. 2 is a rear elevational view of a portion of the board enlarged and showing one of the switch units attached, the cover of the switch unit being omitted for the sake of clearness.

Fig. 3 is a vertical sectional view taken 65 substantially upon the plane of line III of Fig. 2.

Fig. 4 is a horizontal sectional view taken substantially upon the plane of line IV of Fig. 3, and

Fig. 5 is a diagrammatic view, on a reduced scale, illustrating one of the complete switch units.

Referring to the drawings for describing in detail the structure which is illustrated 75 therein, the reference character L indicates that portion of the device which is herein referred to as the board structure, and the reference character G indicates what is herein referred to as one of the removable 80 switch units, of which there may be as many as desired.

The board structure includes the base plate 1 and the two branch line wire channels 2 spaced apart one at each of the vertical edges of the base plate 1. Extending horizontally between the inner wall members 3 of the branch line wire channels is arranged a plurality of cross members or shelves 4. These are spaced apart and serve 90 as the means for attaching the switch units.

The cross members are preferably identical in construction and method of attachment and each is made up of a pair of angle-irons 5 and 6 connected together and 95 to a shelf plate 7. The opposite ends of the angle-irons are connected with the walls 3 preferably by brackets 8 and rivets 9 and the opposite ends of the shelf plate are connected to the wall members 3 by having 100 downturned flanges 10 thereon fixed by rivets 11. The rear longitudinal edge portion of the shelf plate 7 is fixed between the angle-irons by rivets 12 so as thus to effectively reinforce the angle-irons especially against any tendency to bend toward or away from the base plate 1. In turn, the angle-irons reinforce the shelf plate against

any tendency to bend in a vertical plane. The rearward longitudinal portion of each base plate is inclined downwardly and terminates in a plane somewhat inside of the 5 plane of the outer or rear wall 13 of the channels 2.

The switch units G are each substantially identical in size and construction, and each 10 comprises a front wall member H, a back wall member 14, opposite side wall members 15 and 16, a top wall member 17, and a bottom wall member 18.

The top and bottom wall members 17 and 18 are connected with the side wall members 15 by having flanges 19 thereon to which the 15 side wall members are riveted.

The front wall member is connected with the top and bottom wall members by screws 20 or the like 20 which engage flanges 21 formed at the front edges of said top and bottom wall members.

The rear wall member 14 is pivotally supported by the hinges 22 to the rearward edge 25 of the side wall member 15 and constitutes a door which may be opened or closed for controlling access to the container. It is provided with a spring catch 23 for engaging the opposite side wall member 16. A flange 24 at the free edge of the door is 30 adapted to lap over the forward edge of the wall member 16 when the door is closed. Top and bottom flanges 25 and 26 are also provided for stiffening the door and for bridging the space between the main plane 35 of the door and the rear edge of the wall members 17 and 18.

The bottom wall member 18 is preferably inclined to correspond to the inclination of the shelf plates 7 and the object is first to 40 stiffen the structure and second to prohibit the laying down of tools or other devices which might objectionably affect the contents of the container.

All of the wall members are of sheet 45 metal excepting the front wall member H and this is preferably of insulating material such as slate or the like so that it is better adapted for the attachment of current carrying parts of the switch mechanism.

50 Here it should be noted that although the present invention is particularly adapted for use in connection with such a switch mechanism as is shown and described in my co-pending application above referred to, nevertheless it is obvious that other types of 55 electrical devices may readily be employed and that any part or parts of said devices which are mounted on the inner face of the wall member H are entirely concealed and 60 protected whenever the door is closed.

In order to accommodate the type of switch mechanism shown in the pending application above referred to the side wall members 15 and 16 are formed with forward 65 extensions 27, reinforced by strengthening

beads 28 and having the pivot bearings 29 and the slots 30 and 31 for accommodating parts of the switch mechanism. Of course the features 29, 30 and 31 may be altered to suit the different types of devices which may 70 be mounted.

Each of the wall members 15 is preferably formed with an opening 32 through which branch line wires may lead into the container from the wire channels 2, the walls 75 3 of the wire channels of course being also provided with openings, as 33, to register with the openings 32.

As a simple means for attaching the units, the angle-irons 5 and 6 are each provided 80 with threaded apertures 34 therein arranged in pairs and disposed to register with apertures formed through the front wall member H of the respective switch units so that screws, as 35, inserted through the apertures in the wall H engage within the apertures 34. The screws also extend through apertures formed in the flanges 21 of the top and bottom wall members 17 and 18.

The cross members or shelves 4 define a 90 plurality of superposed compartments between the wire channels 2 and each of these compartments is adapted to receive two switch units arranged side by side so that each switch unit has its outer side wall member 15 lying adjacent to one of the walls 3 of the wire channels. Branch line wires may thus be easily threaded through its mating apertures 32 and 33 into all of the containers. 95

In the structure illustrated the base plate 1 carries bus bars 36 at its rear face. It will be noted that where switch mechanism carried by the switch units is adapted to cooperate with these bus bars, the fixed position of the angle-irons 5 and 6 with relation to the bus bars positively determines the position of the switch units, and hence of the switch mechanism, by the simple act of attaching the switch units to the angle-irons. 100

Referring to Fig. 5, it will be noted that the front plate H carries fuse or like parts 37 upon its inner face and switch contact parts 38 upon its outer face arranged to be engaged by the blades 39 which are held by the carrier 41, said carrier being rotatably mounted by means of the extensions 27 from the side walls 15 and 16 of the container. The operating mechanism, as 41, for the carrier 40 is partly arranged within the 115 container and includes a control link 42 extending into connection with the door, as at 43. The parts 37 and 38 are electrically connected through the wall H, as at 44, and the portion of the switch operating mechanism which is arranged within the container, together with said parts 37 are of course protected by the walls of the container, and the blades 39 exteriorly of the container are adapted to connect the contacts 120 125 130

38 with the bus bars at will. A link 45 also extends forwardly from the operating mechanism 41 and is adapted to extend through the face plate 1 of the switch board and to be operated by a handle 46 mounted in a bracket at the front face of the base plate.

As many changes could be made in this construction without departing from the scope of the invention as defined in the following claims, it is intended that all matter contained in the above description or shown in the accompanying drawings shall be interpreted as illustrative only and not in a limiting sense.

15 Having thus described my invention, what I claim as new and desire to secure by Letters Patent is:

1. In a structure of the class described, a base plate, means carried by the base plate comprising a wire channel, a switch or the like container, means supporting said container adjacent the wire channel, and said container and said wire channel having mating openings through adjacent walls thereof 25 through which openings wires may extend from the channel into the container.

2. In a structure of the class described, a base plate, means carried by the base plate providing a pair of wire channels spaced apart and extending side by side along one face of the base plate, a plurality of shelf members extending between said wire channels and being fixed to the walls thereof, said shelf members being spaced apart along 35 the length of the wire channels so as to define a plurality of compartments longitudinally between the wire channels, a pair of switch or the like containers arranged side by side within one of said compartments, 40 means connecting said containers with the adjacent shelves, each of said containers having one of its side walls disposed adjacent to a wall of one of said wire channels respectively, and the adjacent walls of the containers and wire channels having mating 45 openings therethrough through which wires may extend from the wire channels into the containers.

3. In a structure of the class described, a base plate, means carried by the base plate comprising a pair of wire channels spaced apart and extending side by side along one face of the base plate, those walls of the two wire channels which are farthest spaced 55 from the base plate being disposed in a common plane substantially parallel with the mentioned face of the base plate, wire channels serving to define a partially inclosed space at said mentioned face of the base 60 board, a plurality of independently formed and independently removable switch or the like containers arranged within said space, each of said containers having a door provided as one wall thereof and being removable therewith, and the doors of the several 65

containers lying substantially in said mentioned common plane and collectively constituting a protecting wall for said space.

4. In a structure of the class described, a base plate, a plurality of independently formed switch or the like containers each having an independently openable door at one side thereof, and supporting means carried by the base plate whereby to support all of said containers from the base plate. 70

5. In a structure of the class described, a base plate, a plurality of shelves arranged to define compartments at one side of the base plate adapted to receive switch or the like mechanisms, each of said shelves comprising a substantially horizontally disposed shelf plate, and means providing a pair of vertically disposed flanges extending above and below the shelf plate whereby to stiffen the shelf plate and serve as attaching means 80 for said mentioned mechanisms.

6. In a structure of the class described, a base plate, a plurality of shelves arranged to define compartments at one side of the base plate adapted to receive switch or the like mechanisms, each of said shelves comprising a substantially horizontally disposed shelf plate, and a pair of angle irons extending longitudinally of the shelf plate being fixed each by one of its flanges to the 90 marginal portion of the shelf plate one at the upper surface and one at the lower surface of the shelf plate, one having its second flange extending vertically above the shelf plate and the other having its second flange extending vertically below the shelf plate, so as to reinforce the shelf plate and so that the second flanges of said angle irons constitute attaching means for said mentioned mechanisms. 100

7. In a structure of the class described, a base plate, a plurality of independently formed switch or the like container units each consisting of top, bottom and side walls and each having an independently openable door for giving access thereto, and supporting means carried by the base plate whereby to detachably support all of said container units from the base plate. 105

8. In a structure of the class described, a base plate, a plurality of independently formed switch or the like container units each consisting of top, bottom and side walls and each having an independently openable door for giving access thereto, a plurality of substantially horizontally disposed shelves carried by the base plate, and means whereby to detachably connect said container units to and between said shelves. 110

9. In a structure of the class described, a base plate, a plurality of independently formed switch or the like container units each consisting of top, bottom and side walls and each having an independently openable door for giving access thereto, means form- 125

ing wire channels spaced apart upon one surface of the base plate, shelves extending between and supported by said wire channel forming means, and means for detachably connecting said container units to said shelves.

10. In a structure of the class described, a base plate, a plurality of independently formed switch or the like container units each consisting of top, bottom and side walls and each having an independently openable door for giving access thereto, a plurality of substantially horizontally disposed shelves carried by the base board at one side thereof, a bus bar extending along the same side of the base board between the

same and said shelves, means detachably connecting the container units to said shelves of a character to hold the container units spaced from the mentioned side of the base board, and certain of the walls of each container unit having extending portions projecting into said space adapted to support a switch device for coöperation with said bus bar. 20 25

In testimony whereof I affix my signature in the presence of two witnesses.

HUBERT F. KRANTZ.
